ABSTRACT

Adhesive binding folder for binding loose sheets with two outside enclosing covers, joined to each other by a back strip which carries a double self adhesive layer against which the narrow rear edges of the bound inner sheets are positioned. The layer includes a removable strip to expose the adhesive and thereby adhere to the sheets. An inner protective sheet for the purpose of attachment penetrates with a narrow margin into the contact interface of the self adhesive layer. Said sheet serves to cover the self-adhesive layer laid bare by pulling out individual sheets.

ADHESIVE BINDING COVER

CROSS-REFERENCE TO RELATED APPLICATION

This application is a continuation of application Ser. No. 97,412, filed Dec. 3rd, 1970, now abandoned.

SUMMARY OF THE INVENTION

The invention relates to an adhesive binding folder with two outside enclosing covers, joined to each other by a back strip. The strip carries a self-adhesive layer against which the narrow rear edges of the bound inner sheets are positioned. The layer includes a removable strip to expose the adhesive and thereby adhere to the sheets.

The conventional back strips connecting the enclosing covers consist of relatively thick material. This is necessary for applying a sufficiently thick self-adhesive layer to the back strip. However, inconvenience in folding and adjusting of the back strip to the narrow edges of the sheets is usually encountered.

Unfortunately, pliable back strips of thinner material do not possess the required amount of a thinner adhesive coating, so that the loosely bound sheets are not firmly retained.

Thus the problem encountered by the prior art consists in providing an adhesive binding folder comprising a back strip which joins the enclosing covers and, to ensure an easy folding movement of the enclosing covers, is made of thin material, additionally the choice of thin material must possess a secure adhesive bond to prevent self-release of the individual-bound sheets. An additional requirement is the formation of an adhesive binding folder to prevent the sticking of the topmost sheet to the self-adhesive layer exposed by the pulling out of individual sheets.

The present invention suggests a self-adhesive layer of the back strip formed double between the edges of the enclosing covers facing each other by means of a transfer strip adhesively secured in this zone.

The outer edges of the twofold adhesive layer are spaced from the opposing parallel edges of the enclosing covers and secured thereto.

The invention further suggests a protective sheet projecting into the contact interface of the two self-adhesive layers.

The invention further envisions an inner protective sheet made of a thin plastic foil.

The invention consists in an adhesive binding folder with two outside enclosing covers interconnected by a back strip having an inward self adhesive layer against which are applied the thin rear edges of the bound inner leafs.

The invention produces an adhesive binding folder whose back strip determined by the structural height of thin material ensures a secure bond with the individual sheets held by it. Despite the thinness of the back strip a double self-adhesive coating is provided between the opposing edges of the enclosing covers. By this design, the individual sheets are pressed into a reliable bond with the adhesive layer of the back strip. In addition, the folding and closing of the adhesive binding folder is improved. The simplest way of obtaining the double self-adhesive layer is by attaching a transfer strip to the self-adhesive coating of the back strip. The latter performs a double function. On the one hand, it serves to

cover the bared self-adhesive layer of the back strip before the individual sheets have been bound in, and, on the other, the self-adhesive coating, for instance of siliconized carrier strip material, upon it becomes attached to the self-adhesive layer of the back strip.

The outside edges of this two-fold adhesive layer, which are spaced from the opposing edges of the enclosing covers, create conditions advantageous to the binding in of loose sheets. In addition the folder is even easier to fold. The latter is especially advantageous in the case of full folders, because there is no crushing at the edges of the folder. The two self-adhesive layers greatly facilitate the provision of an inner protective leaf, which for the purpose of attachment penetrates with a narrow margin into the contact interface of the self-adhesive layers. This inner protective leaf serves to cover the self-adhesive layer laid bare by pulling out individual sheets to prevent the flat adhesion of the sheet left topmost. Thin plastic foil is particularly suitable as material for the inner protective leaf. The secure contact of the flat margin of the inner protective leaf with the self-adhesive layer of the back strip exposed by the tearing out of individual leaves is expedited by giving an electrostatic charge to the inner protective leaf of plastic foil.

BRIEF DESCRIPTION OF DRAWINGS

The invention will now be described by way of example with reference to the drawings in which

FIG. 1 is an elevation of the adhesive binding folder according to the first embodiment of the invention;

FIG. 2 is a top view of the unfolded back strip joining the enclosing covers by the transfer strip;

FIG. 3 is a section view along line III—III in FIG. 2 in magnified diagrammatic presentation;

FIG. 4 is similar to FIG. 3 with the carrier strip material removed;

FIG. 5 is a section view through the adhesive binding folder with individual leaves emplaced;

FIG. 6 is a second form of embodiment according to FIG. 3 incorporating an inner protection leaf;

FIG. 7 is a section view of an adhesive binding folder provided with an inner protection leaf and bound sheets; and

FIG. 8 is similar to FIG. 7 with individual sheets partly removed.

In the embodiment illustrated in FIGS. 1 to 5 the adhesive binding folder includes enclosing covers 1 and 2 interconnected by a back strip 3. The latter is inwardly provided with a self-adhesive coating 4.

In the portion between the parallelly aligned opposing edges 1' and 2' of the enclosing covers 1 and 2, a transfer strip 5 is secured over the self-adhesive layer 4 of the back strip 3. This transfer strip 5 consists of a carrier strip 7, one side of which is provided with a coating of silicone 6. A second adhesive layer 8 is arranged upon the said silicone layer 6.

The secondary adhesive layer 8 is deposited against the self-adhesive layer 4 of the back strip. The second adhesive layer 8 is adjusted to the back strip 3 to dispose the outer margins 8' of the adhesive layer 8 a distance x from the opposing edges 1' and 2' of the enclosing covers 1 and 2.

To bind a stack of sheets made up of individual leaves 9 the carrier strip 7, provided with the silicone layer 6, is removed while the second adhesive strip 8 maintains its bond with the self-adhesive layer 4. In this way, a

double self-adhesive layer is obtained on the back strip 3 in the zone between the opposing edges 1' and 2' of the enclosing covers 1 and 2, the said layer entering into an intimate bond with the narrow rear edges 9' of the individual leaves 9.

Owing to the space x , the binding-in of the individual leaves 9 is made easier. Further, this space x , which is at least as wide as the thickness measurement of the enclosing cover 1 or 2, facilitates the folding of the adhesive binding folder.

The embodiment shown in FIGS. 6 to 8 incorporates an inner protective leaf 10. This inner protective leaf, made of a thin plastic foil, projects with its narrow margin 10' into the contact gutter F of the two self-adhesive layers 4 and 8. Once the carrier strip 7 has been pulled back, the second adhesive layer becomes attached to the adhesive layer 4 and to the margin 10' of the inner protective leaf 10. Accordingly, the individual leaves 9 can be brought into adhesive bond with the exposed double adhesive layer.

If, beginning with FIG. 7, individual leaves 9 are withdrawn from the adhesive binding folder by being pulled off from the self-adhesive layer 8, the self-adhesive layer 4 will be partly exposed. To prevent this from entering into a flat bond with the topmost individual sheet, the inner protective leaf 10 covers the exposed self-adhesive layer — see FIG. 8. The secure contact of the sectional area of the inner protective leaf 10 with the bared self-adhesive layer may be expedited by an electrostatic charge upon the inner protective leaf 10, which is made of thin plastic foil.

What I claim is:

1. An adhesive binding folder comprising: a backing strip; a first coating of self-adhesive material having a first surface, said coating having a substantially uniform thickness and being attached to said backing strip on one surface thereof; two outside enclosing covers which are directly attached to a second surface of said first adhesive coating opposite said backing strip so as

to be attached to said one surface of said backing strip by said first adhesive coating, said covers being attached to opposite elongated margins of said backing strip leaving adhesive exposed in the central area of the strip between edges of the covers; and a second coating of self-adhesive material of a substantially uniform thickness covering only a portion of said first adhesive coating and having one entire surface attached to said first adhesive coating, said second adhesive coating being disposed exclusively in the area between the two outside covers whereby individual leaves can be attached to said second adhesive coating between said covers and the total thickness of adhesive being greater in the area covered by said second coating than in the area covered only by said first coating; a carrier strip having a silicone coating on one surface thereof and being attached to said second adhesive coating along the surface having said silicone coating on the side opposite said backing strip and capable of being easily removed from said second coating, whereby the individual leaves can then be attached to said second coating; and an inner protective sheet having an edge zone extending along one of said elongated margins, said zone being interposed between said first adhesive coating and said second adhesive coating, said inner protective sheet being arranged so as to cover at least a portion of the outer surface of said second adhesive coating for covering adhesive exposed by removal of individual leaves.

2. Adhesive binding folder as set forth in claim 1, wherein said second adhesive coating is spaced from each of said covers by a predetermined distance, which is at least equal to the thickness of said covers, when the covers are in an open position.

3. Adhesive binding folder as set forth in claim 1 wherein said inner protective sheet is made of a thin plastic foil.
